(57) CLAIM

I claim the ornamental design for the pipette tip, as shown and described.

DESCRIPTION

FIG. 1 is a perspective view of a pipette tip showing my new design;

FIG. 2 is a bottom view thereof; and

FIG. 3 is a side view thereof.

FIG. 4 is a perspective view of a second embodiment of a pipette tip showing my new design;

FIG. 5 is a bottom view thereof; and,

FIG. 6 is a side view thereof.
